PRODUCTION OF SOLVENTS

Harry E. Bloomsburg, Westfield, N.J., and Oral C. Behymer and William K. Robbins, Baytown, Tex., assignors, by mesne assignments, to Esso Research and Engineering Company, Elizabeth, N.J., a corporation of Delaware

Filed Oct. 15, 1958, Ser. No. 767,488

6 Claims. (Cl. 208—312)

The present invention is directed to a method for improving the odor of solvents. More particularly, the invention is concerned with producing solvents of improved odor by rejecting compounds which cause odor in such solvents. In its more specific aspects, the invention is directed to improving the odor of solvents by combining a selected fraction with the saturated constituents of the solvent.

The present invention may be briefly described as a method for improving the odor of solvents in which a hydrocarbon fraction containing aromatic and saturated hydrocarbons and odoriferous compounds boiling in the range from about 100° to about 450° F. is subjected to solvent extraction to form a raffinate phase and an extract phase. The raffinate and extract phases are freed of solvent and the solvent-free extract phase is then distilled to reject light and heavy aromatic compounds and the odoriferous compounds contained therein to obtain a heart cut fraction distilling between about 40 percent and about 90 percent of the extract phase. The heart cut fraction and the raffinate phase may be sweetened or hydrofined after combination or prior to combination, as may be desired.

The solvent employed in the practice of the present invention is preferably sulfur dioxide and may be used at temperatures in the range from about 0° to —60° F. A solvent-to-hydrocarbon ratio of about 50 to 200 may be employed in the present invention. Other selective solvents may be used, such as phenol, diethylene glycol, furfural, or adsorbents such as silica gel, and the like may be used.

The hydrocarbon fraction is preferably a hydrocarbon obtained from crude petroleum and may boil in the range from about 100° to about 450° F. and usually boils in the gasoline boiling range. Fractions boiling in the kerosene range may also be employed. This hydrocarbon fraction contains saturated hydrocarbons and aromatic hydrocarbons, as well as odoriferous compounds which may be aromatic-type compounds.

It has been discovered that the odoriferous compounds are concentrated in the 0 to 40 percent fraction of the extract phase and the 90 to 100 percent fraction of the extract phase. This is indeed surprising since ordinarily it would be expected that odor-forming or odoriferous compounds in fractions of this nature would normally be concentrated only in the heavier fractions. By virtue of this discovery, it is now possible to improve the odor of solvents by selectively rejecting the aromatic hydrocarbons which contain the odor-forming or odoriferous compounds.

It is desirable to sweeten the raffinate and fractions of the extract phase and this may either be done separately or after combining the fractions in accordance with the present invention. The sweetening operation may suitably be a hypochlorite operation such as described in U.S. Patent No. 2,626,232 to Love. Other sweetening operations may be used, such as cupric chloride, sodium plumbite, the tannin solutizer process, and the like.

The present invention will be further illustrated by ref-

2

erence to the drawing which is a flow diagram of the preferred method.

Referring now to the drawing, numeral 11 designates a charge line by way of which a virgin naphtha is introduced into distillation zone 12 which is shown as a single distillation tower but which may be a plurality of distillation towers. In any event, distillation zone 12 is provided with suitable vapor-liquid contacting means, means for inducing reflux and auxiliary condensing and cooling means usually associated with a modern distillation tower. Zone 12 is shown as being provided with a heating means illustrated by steam coil 13 which is employed to adjust temperatures and pressures. Zone 12 is operated to obtain, by way of line 14, a fraction boiling in the range from about 100° to about 450° F. which is introduced by line 14 into a solvent extraction zone 15. Heavier fractions are discharged from the zone 12 by line 16 for further use as may be desired.

The solvent naphtha fraction introduced into zone 15 by line 14 contacts countercurrently a solvent such as sulfur dioxide introduced into zone 15 by line 17. It is understood, of course, that zone 15 is provided with internal liquid-liquid contacting means to provide intimate contact between the liquid solvent and the hydrocarbon. Under the conditions of temperature and solvent-to-hydrocarbon ratios mentioned before, an extract phase and a raffinate phase are formed in zone 15, the raffinate phase being withdrawn by line 18 while the extract phase is discharged by line 19. The raffinate phase is introduced into a solvent stripper 20 provided with a heating means such as steam coil 21 for removal of solvent by line 22 from the raffinate phase, the raffinate phase free of solvent discharging from stripper 20 by line 23.

The extract phase in line 19 is likewise introduced into a solvent stripper 24 provided with a heating means such as 25 to cause removal of the solvent from stripper 24 by line 26 and to allow the withdrawal of a solvent-free extract by way of line 27.

The solvent-free extract is introduced by line 27 into a distillation zone 28 which is similar to distillation zone 12 being provided with all auxiliary equipment for performing its necessary function. Zone 28 is provided with a heating means such as steam coil 29 for adjustment of temperatures and pressures. By proper control of temperatures and pressures, a light fraction is removed from zone 28 by line 30 which may comprise from 0 to 40 percent of the extract introduced by line 27, while a heavier fraction comprised of 90 to 100 percent of the extract is withdrawn by line 31. A heart cut fraction is withdrawn from zone 28, which may comprise 40 to 90 percent of the extract, by way of line 32.

It is to be noted that a line 33 controlled by a valve 34 is provided and this is to allow the obtaining of heart cut fractions of varying width. For example, it may be desirable to obtain a 50 to 90 percent heart cut fraction or a 60 to 90 percent heart cut fraction. In that event, a 0 to 50 percent or a 0 to 60 percent fraction might be obtained by line 32 or selected fractions might be obtained by line 32 and the desired fraction by line 33. In any event, line 32 and line 23 are controlled, respectively, by valves 35 and 36 and the two lines connect and merge into line 37 to allow combining or blending of the raffinate phase in any desired proportion. The combined raffinate phase and the fraction of the extract phase are then sweetened in a sweetening or hydrofining zone 38 which may be one of the type illustrated from which an improved odor solvent is obtained by line 39 for use as desired in the dry cleaning industry, in extraction of foodstuffs, in paints, varnish, protective coatings, and the like, where odor is a problem. Solvents of good odor having kauri butanol values within the range from about 35 to about 40 are obtainable in the present invention.

It may be desirable to sweeten the raffinate phase and the fraction of the extract phase separately and, to this end, either valve 35 or valve 36 may be closed, depending on which fraction is to be sweetened first, with the other fraction being stored in storage tanks (not shown) prior to its separate sweetening.

It is also contemplated that the two fractions may be blended in the ratio of the extract phase to the raffinate phase such that a solvent of improved odor and solvency value is obtained. By blending the selected heart cut fraction of the extract phase and the raffinate phase in the ratio of the extract to raffinate, a solvent of improved solvency value is obtained. It is to be understood that any blend may be made to a selected solvency value ordinarily and preferably not less than the solvency value of the fraction subjected to solvent extraction.

The invention will be further illustrated by reference to the following runs wherein a hydrocarbon designated as Varsol No. 1 and boiling in the range from about 300° to 400° F. was subjected under solvent extraction conditions to extraction with sulfur dioxide at a temperature of -10° to -30° F. The extract phase free of solvent was then fractionally distilled to obtain various fractions of the extract phase which were then combined in the ratio of the extract to raffinate to obtain solvents of varying odor ratings. The results of these operations are presented in the following table.

Table I

Composition:				
Varsol No. 1, Percent	100			
Raffinate, Percent		82	82	82
60-90% Extract Fraction, Percent		18		
50-90% Extract Fraction, Percent			18	
50-90% Extract Fraction, Percent				18
Inspections:				
Aromatics	16.8	18.2	17.9	17.6
Kauri butanol Value	39.0	39.8	39.6	39.9
Odor Rating in Order of Preference	4	1	2	3

It will be noted that the odor rating of the Varsol No. 1 is substantially greater than the odor rating of the several blends with the 60 to 90 percent extract fraction giving the most desirable result. It is to be further noted that the practice of the present invention provides a solvent of increased aromaticity and of appreciated kauri butanol value which is a measure of the solvency value of the solvent. In other words, the practice of the present invention not only improved the bulk odor of the solvent but also improved the solvency value thereof.

In accordance with the present invention, the odor of solvents is improved by solvent extracting the aromatics from a hydrocarbon fraction of the desired boiling range and then distilling the extracted aromatics to reject the lighter aromatic hydrocarbons for use as may be desired such as in gasoline while the aromatic hydrocarbons comprising from about 40 to about 90 percent of the solvent extract are added to the solvent raffinate to provide a solvent of the desired solvency requirement and of improved odor, the aromatic odor impact of the finished solvent being improved.

In the present invention the desirable aromatics are concentrated and employed in the finished solvent providing desirable properties thereto. For example, when used in paints, the paint film is conditioned on drying since the first fractions which evaporate may be fractions of lower solvency whereas the remaining fractions may be of higher solvency. Solvents prepared in accordance with the present invention are therefore useful in paints providing continuity, levelling, and adherence of the paint or varnish film.

Furthermore, the present invention allows production of solvents of varying and selected quality as may be required. Thus, if a solvent of 35 kauri butanol value is desired, this may be accomplished by adding the selected aromatic fraction to the solvent raffinate in an amount within the range from about 8 percent to about

12 percent by volume to provide the desired characteristics to the solvent and impart to the paint the qualities required. Of course, such a solvent will be of improved odor. Likewise, to obtain a higher kauri butanol value

solvent, amounts of the selected aromatic fraction within the range from about 16 percent or 18 percent by volume may be added to the raffinate. In short, in accordance with the present invention, solvents of any desired solvency value and of improved odor are obtainable by adding the selected aromatics to the solvent raffinate in sufficient amounts to provide a solvent having a kauri butanol value in the range from about 35 to about 40.

The present invention is therefore of importance and utility.

The nature and objects of the present invention having been completely described and illustrated, what we wish to claim as new and useful and to secure by Letters Patent is:

1. A method for improving the odor of solvents which comprises solvent extracting a hydrocarbon fraction boiling in the gasoline and kerosene range containing aromatic and saturated hydrocarbons and odoriferous compounds to form a raffinate phase and an extract phase, separately removing and recovering solvent from said phases, distilling the solvent-free extract phase to separate and recover a heart cut fraction including aromatic hydrocarbons distilling between about 40% and about 90% of said extract phase and to separate and reject odoriferous compounds, and then combining said heart cut fraction with said raffinate phase whereby a solvent of improved odor and solvency value is obtained, said heart cut fraction and said raffinate phase being sweetened after separation and recovery of said heart cut fraction from said solvent-free extract phase by distillation.

2. A method for improving the odor of solvents which comprises solvent extracting a hydrocarbon fraction containing aromatic and saturated hydrocarbons and odoriferous compounds boiling in the range from about 100° to about 450° F. to form a raffinate phase and an extract phase, separately removing and recovering solvent from said phases, distilling the solvent-free extract phase to separate and recover a heart cut fraction including aromatic hydrocarbons distilling between about 40% and about 90% of said extract phase and to separate and reject odoriferous compounds, and then combining said heart cut fraction with said raffinate phase in the ratio of extract to raffinate whereby a solvent of improved odor and solvency value is obtained, said heart cut fraction and said raffinate phase being sweetened after separation and recovery of said heart cut fraction from said solvent-free extract phase by distillation.

3. A method in accordance with claim 2 in which the heart cut fraction and raffinate phase are sweetened after combination.

4. A method in accordance with claim 2 in which the heart cut fraction and raffinate phase are sweetened separately prior to combination.

5. A method for improving the odor of solvents which comprises solvent extracting a hydrocarbon fraction containing aromatic and saturated hydrocarbons and odoriferous compounds boiling in the range from about 100° to about 450° F. with sulfur dioxide to form a raffinate phase and an extract phase, separately removing and recovering sulfur dioxide from said phases, distilling the sulfur dioxide-free extract phase to separate and recover a heart cut fraction including aromatic hydrocarbons distilling between about 40% and about 90% of said extract phase and to separate and reject odoriferous compounds, then combining said heart cut fraction with said raffinate phase in the ratio of extract to raffinate, and sweetening the combined heart cut fraction and raffinate phase, whereby a solvent of improved odor and solvency value is obtained.

6. A method for improving the odor of solvents which

comprises solvent extracting a hydrocarbon fraction containing aromatic and saturated hydrocarbons and odoriferous compounds boiling in the range from about 100° to about 450° F. to form a raffinate phase and an extract phase, separately removing and recovering solvent from said phases, distilling the solvent-free extract phase to separate and recover a heart cut fraction including aromatic hydrocarbons distilling between about 60% and about 90% of said extract phase and to separate and reject odoriferous compounds, then combining said heart 10

cut fraction with said raffinate phase in the ratio of extract to raffinate, and sweetening said combined heart cut fraction and raffinate phase whereby a solvent of improved odor and solvency value is obtained.
